Des. 212,600
Patented Nov. 5, 1968

212,600

CART FOR FIREWOOD

Frank J. Bequette, Jr., 219 Tungsten St.,
Henderson, Nev. 89015

Filed Feb. 12, 1968, Ser. No. 10,544

Term of patent 14 years

(Cl. D14—3)

FIG. 1 is a perspective view of a cart for firewood showing my new design;

FIG. 2 is a front elevation thereof;

FIG. 3 is a rear elevation thereof;

FIG. 4 is an elevational view taken from one side thereof;

FIG. 5 is a top view; and

FIG. 6 is a bottom view.

I claim:

The ornamental design for a cart for firewood, as shown.
